UNITED STATES PATENT OFFICE

JAMES L. McCOSH, OF TULARE, CALIFORNIA

CABINET

Application filed December 14, 1928. Serial No. 326,055.

This invention relates to cabinets and has particular reference to a cabinet for storing and displaying garments, curtains, draperies, silks, yard goods or any other fabrics or articles of this general character.

The primary object of the present invention is to provide a display cabinet which shall be capable of receiving a large number of articles in a minimum space and still present a neat appearance therein and each be readily accessible for removal from the cabinet for display or other purposes.

Another object is to provide a display cabinet in which the articles shall be arranged in a neat and attractive order and which shall effectively protect the articles from dust and dirt so that they will always present a fresh and salable appearance.

A further object is to provide a cabinet of the aforesaid character which shall be attractive in appearance, simple in construction, and inexpensive to manufacture.

With these and other objects in view, the invention may be stated to consist in the various novel features of construction and arrangement or combination, all of which will be fully described hereinafter and pointed out in the appended claim.

In the drawings, accompanying and forming part of this application,

Figure 1 is an elevation of a cabinet constructed in accordance with my invention;

Figure 2 is a vertical sectional view therethrough; and

Figure 3 is a horizontal sectional view taken on the line 3—3 of Figure 2.

A cabinet embodying my invention comprises a base plate 1 which is preferably fitted with casters 2 to facilitate movement of the cabinet to any desired location. A boss 3 rises from the central portion of the base and is formed with a threaded bore to receive a tubular standard 4. The peripheral edge portion of the base is provided with two annular guides or tracks 5 and 6, each of which is formed with a ball race 7. Journalled in each of these guides or tracks are two segmental sub-base portions 9, each subtending an arc of slightly more than 90° as shown in Figure 3. Suitable anti-friction

bearings 10 are interposed between the fore-mentioned guides or tracks and the sub-bases, so that the latter may rotate freely on the base. Each sub-base extends upwardly and outwardly and is provided at its upper edge with a groove to receive an arcuate panel 11 which is preferably glass so that the goods will be visible when in the cabinet.

Fastened to the upper portion of standard 4 by means of a set screw 14 is a collar 15 which carries a thrust bearing 16 and on which rests a hood denoted generally at 17. This hood is substantially circular in plan view and is formed at its center with a depending and vertically disposed sleeve portion 18 that receives the upper end portion of the standard 4. The lower end portion of sleeve 18 is deflected laterally at 19 to engage the thrust bearing 16 and form a rotatable support for the hood, and thence upwardly as at 20, where it terminates in an inwardly directed circular trough 21. The outer circumferential edge portion of the hood 17 is rolled downwardly, inwardly and thence upwardly as at 22 to define a support for the outer ends of a plurality of material supports denoted generally at 23. The inner ends of these material supports engage over a ring 24 located in trough 21. The details of the material supports are set forth in my copending application, Serial Number 326,054, filed December 14, 1928, and hence a detailed description thereof is deemed unnecessary in this application, it being sufficient to state that the material supports are detachably connected to the cabinet in the above described manner and each support is provided with an extensible arm 25 which is adapted to be wholly within the cabinet, as shown in Figures 1 and 2, or which may be extended to a position outside of the cabinet.

A cover plate 30 is fastened to the upper end of the standard 4 by means of an ornamental screw 31, and is formed at its marginal edge portion with concentric annular grooves 32 to slidably receive the upper edges of the aforementioned arcuate panels 11.

In use, one or more of the cabinets may be easily moved or arranged in the desired location, to most effectively display the goods.

Access is gained to the cabinet by sliding one or more of the arcuate panels 11 and sub-bases 9 on the circular tracks in which they are mounted. When storing articles in the cabinet, any desired number of material supports 23 may be placed in the cabinet. That is, if drapery materials are being stored, it is obvious that considerably more could be placed therein than if heavy garments such as coats were being stored. Obviously it is desirable that no empty material supports be in the cabinet which would detract from the general appearance of the display, hence the detachable feature of the material supports is highly desirable. Having filled the cabinet with articles, it will be noted that each occupies an individual support and hence any article may be removed from the cabinet without disturbing the others. This is accomplished by sliding back one or more of the panels 11 to gain access to the particular article, then pulling outwardly on the support 25, thereby positioning the article outside of the cabinet. If desired the tubular support 25 may be completely removed from the rod on which it telescopes thereby permitting removal and inspection of the article in a different light while still maintaining it in a display position over the arm 25.

When all of the panels 11 are closed, the articles are completely protected from dust and dirt so that they will always present a fresh and salable appearance. Furthermore, by making the panels 11 of glass, and arranging the article in radial positions, they are readily observed even when protected from dust and unnecessary handling.

What I claim is:—

A cabinet comprising a circular base, a standard rising from said base, a stationary cover carried by said standard of larger diameter than said base, a plurality of sub-bases journalled on said base and extending upwardly and outwardly to define a diameter substantially equal to said cover, a plurality of panels extending between said cover and said sub-bases and carried by said sub-bases, said sub-bases with their respective panels being movable independently of each other, said standard being adapted to revolvably carry material supports within said cabinet.

In testimony whereof I affix my signature.

JAMES L. McCOSH.
